known as "stitchdown shoes," the lower marginal portion of the upper is turned inward and the outer sole, the welt and sometimes the inner sole are secured to the shoe by stitches which do not go to the upper or to the inner sole but do not show in the interior of the shoe. Since these shoes ordinarily have an inner sole and an outer sole, the upper is turned to the right and since the outturned upper adds to the thickness of the marginal portion of the sole, it will be clear that the shoe is not as flexible as might be desired either in children's shoes or those made for adults. Moreover, many stitchdown shoes are of the "one-sole" type in which the upper and middle sole or "liner" is utilized between the inner sole and the outer sole to provide a member which is turned over the upper and placed before the outer sole is applied. Obviously, a shoe of this type is considerably less flexible than shoes of other types.

Another disadvantage in shoes of this character is that they cannot ordinarily be provided with an inner sole, the inner sole being replaced by spaces are provided in the shoe bottom for the introduction of cushioning material. The inner sole is usually a thin padded layer which usually extends over the entire shoe bottom and in most cases contact with one another throughout their entire length. This is undesirable because it reduces the thickness in the shoe and also prevents the incorporation of a layer of cushioning material in the sole portion of the shoe. It is also undesirable to have a surface which would only increase the thickness of the shoe bottom besides tending to render the shoe topless for the heel.

An object of the present invention is to provide improved stitchdown shoes having sole portions which are more flexible than shoes of the same type made heretofore and which are also adapted to cushion the foot.

It is broader objects of the invention provides a stitchdown shoe having a skeletonized inner sole, complementary outer sole construction. In addition to the complementary sole features the shoe is also provided with inner sole and outer sole members of laminated formation having an inner sole material and an outer layer of an outer layer of suitable sole material. In this way the shoe is rendered more flexible than shoes

As illustrated herein the skeletonized inner sole, complementary outer sole construction, and the stitching used in a two-sole stitchdown shoe or in a three-sole stitchdown shoe. In the two-sole shoe the cushioning material may be applied to the inner sole and only the skeletonized sole construction utilized. In the three-sole construction the skeletonized and complementary sole construction in accordance with one aspect of the invention, be incorporated in the inner sole and middle sole or in the inner sole aspect of the sole construction. It is also incorporated in the middle sole and the outer sole. Moreover, as illustrated, the cushioning material can be applied in the same manner as in the case of the edge of the sole portion of the shoe or it may be located within the outturned marginal portions of the upper. The sole, regardless of the thickness of the margin of said sole portion.

With the above and other aspects and features in view, the invention will now be described in connection with the accompanying drawing and thereafter pointed out in the claims.

FIG. 1 is a transverse sectional view through the forepart of a sole blank on which is indicated by broken lines where the sole blank may be split to form a skeletonized insole, complementary outsole combination.

FIG. 2 is a transverse sectional view of the insole-outsole members produced by splitting the blank on the line indicated in FIG. 1, the members being shown separately and not in contact with each other.

FIG. 3 is a transverse sectional view through the forepart of a stitchdown shoe embodying the insole-outsole combination of FIG. 2.

FIG. 4 is a transverse sectional view similar to FIG. 1, in which the sole blank is of laminated construction, showing two locations where the blank may be split to form a skeletonized insole, complementary outsole combination.

FIG. 5 is a transverse sectional view of the insole-outsole members formed by splitting the blank on the line indicated in FIG. 4.

FIG. 6 is a transverse sectional view through the forepart of a stitchdown shoe embodying the insole-outsole construction of FIG. 5 and including a welt.

FIG. 7 is a sectional view, similar to FIG. 6, in

sole-outsole combination may be located about $\frac{1}{4}$ of an inch below the upper surface of the blank, and the raised or elevated portion may be about $\frac{1}{2}$ of an inch thick, and the lower portion may be about three inches thick at all portions except at the forepart where the open portion of the sole is about $\frac{1}{2}$ of an inch thick, and the raised or elevated portion forming the projection may be about six inches thick except at the forepart where the raised or elevated portion forming the projection may be about $\frac{1}{2}$ of an inch thick. If the sole blank 16 is of block formation, that is, if it has not been shaped to the outline of a sole it will be cut out in the usual manner, and the manner of cutting is the splitting operation. The broken line a in Fig. 1 shows the location of the cut at the forepart of the blank.

The splitting operation may be conveniently performed with the aid of a matrix roll splitting machine of the general type disclosed in United States Patent No. 2,068,745, granted on August 3, 1937, on an application filed in the name of C. E. Hood. As disclosed in the patent the splitting operation may be performed, briefly, a single straight edge knife, an adjustable matrix roll, and a feed roll for moving the sole blank 16 toward the cutting edge of the straight edge knife, the matrix roll having a depression or cavity therein corresponding in outline to the shape of the cutting operation to be made. The knife cuts the blank parallel to its own plane at all portions except where the blank passes over the matrix roll, in which case the knife cuts the blank is distorted and the knife cuts distally through the material of the blank to its outer surface, thereby forming an opening in the extraction portion of the forepart of the blank 16 and producing a so-called skeleton inner sole and an outer sole having a projection on its forepart complementary to the opening in the inner sole.

The skeletonized forepart of the inner sole 12 may now be reinforced on its inner side with a portion of the upper 20 which advantageously is $\frac{1}{2}$ of an inch thick, and the inner sole may be assembled on a last 18 in the usual manner with a shoe upper 20 , the margins of the upper being secured to the inner sole 12 as shown in Fig. 3, so that they engage the adjacent portion of the margin of the inner sole 12 . The upper 20 is secured to the inner sole 12 in any usual or convenient manner to the inner sole in any usual or convenient manner, for example, by stitches or, if desired, by fastenings 22 such as staples which are preferably inserted in the center where the marginal portion of the upper is turned outwardly and which extends through the inner sole and are clinched against the outer face. The outer sole 14 is now laid on the shoe bottom in the usual manner, and the upper 20 is secured to the outer sole 14 by any usual or convenient means.

The laminated outer sole may be produced from a laminated blank 28 , such as that illustrated in Fig. 4, which is composed of an upper layer 30 and a lower layer 32 . The upper layer 30 which is to form the inner layer of the outer sole, may be composed of relatively soft, yieldable material such, for example, as cork, felt, or leather, or compositions of a similar, yieldable nature. This upper layer 30 is wide, preferably about one-sixteenth of an inch or the like, and is secured, for example, by cement such as latex, to the lower layer 32 of sole leather or other material, the lower layer 32 being approximately six inches thick.

The laminated blank thus formed is next split in the manner indicated in Fig. 5, to form a skeletonized inner sole, complementary outer sole construction. The blank 28 may be split to form the skeletonized inner sole, complementary outer sole construction indicated by the broken line b in Fig. 4, this location, except at the central portion of the forepart, coinciding with the plane of the cut between the two layers, thereby producing a skeletonized inner sole composed entirely of the yieldable material 30 forming the upper layer of the blank. At the forepart of the blank 28 the knife actually cuts in flat plane but that the distortion of the blank causes the cut to be shaped as shown in Fig. 5 when the blank is reduced to its original flat condition. In order that the inner sole may be reinforced by a thin facing of the more solid material forming the lower layer 32 of the blank, the split is preferably made in the location indicated by the lower broken line c in Fig. 4. Fig. 5 illustrates the skeletonized inner sole 38 and a complementary outer sole 40 produced by splitting the forepart of the laminated blank 28 and the upper 30 on the line b and the rest of the blank, of course, being located in the position indicated by the lowest part of the dashed line.

The complementary insole-outsole members 38 , 40 of Fig. 5 are now incorporated in a two-sole structure, as shown in Fig. 6, in the manner already described in connection with the shoe illustrated in Fig. 3, the skeletonized insole, of which is reinforced by the thin layer of material at least during the lastning operation. As shown in Fig. 6, the upper 44 of the shoe has its marginal portion turned outwardly to overlap the inner sole 38 of the skeletonized insole 38 and the upper is secured in lastned relation to the inner sole by suitable fastenings 46 , such as staples or stitching. The outer sole 40 is positioned on the outer sole 40 completely fills the opening

shaped or rounded outline of a sole in the manner previously described. At the same time, a vertical cut is made through the yielding material forming the upper layer, this cut being located in outline just within the width of the blank as rounded. The portion of the yielding material 52 located outside the vertical cut may then be rounded to a radius which is smaller in outline than the lower layer 54.

Further rounding operations may conveniently be performed on a double knife sole rounding machine such, for example, as that disclosed in Letters Patent of the United States No. 2,077,064, granted October 20, 1936, or an application filed in the name of Frederic E. Bertrand. As described in the patent referred to, the blank is provided with a knife for rounding to the full thickness of the blank and has a second knife concentric and adjacent to the first, the second being on the upper surface of the blank, this being spaced a predetermined distance inwardly from the cut made by the first knife. The second knife can be adjusted heightwise of the blank to produce a vertical cut of the desired depth so that this cut will extend only to the plane of adhesion between the yielding material 52 and the lower layer 54 of the blank.

In the manner described, it is split preferably in the matrix roll splitting machine to provide a sole 56 and a liner 58, the inner sole 56 having a projection on its forepart complementary to the opening in the inner sole. The sole 56 is then turned into the skeletonized insole, complementary outsole combination 56, 58, should, in the present invention, be made a second distance below the plane of adhesion between the layers of the blank than it was in the construction shown in FIG. 6 so that a complementary sole, such as fabric or sole blank material, such as leather, will be provided on the lower surface of the skeletonized insole 56, the provision of which is termed a feather portion of substantial thickness which coincides with the periphery of the outsole 58 and the liner 56.

In constructing a shoe in accordance with the present aspect of the invention, a shoe upper 60 is secured in lasted relation to the inner sole

type, constructing the shoe illustrated in FIG. 8 and 9 in which the upper 60 is a stitched-down shoe having a combination of sole members 62, 64, 66, 68, 70, 72, 74, 76, 78, 80, 82, 84, 86, 88, 90, 92, 94, 96, 98, 100, 102, 104, 106, 108, 110, 112, 114, 116, 118, 120, 122, 124, 126, 128, 130, 132, 134, 136, 138, 140, 142, 144, 146, 148, 150, 152, 154, 156, 158, 160, 162, 164, 166, 168, 170, 172, 174, 176, 178, 180, 182, 184, 186, 188, 190, 192, 194, 196, 198, 200, 202, 204, 206, 208, 210, 212, 214, 216, 218, 220, 222, 224, 226, 228, 230, 232, 234, 236, 238, 240, 242, 244, 246, 248, 250, 252, 254, 256, 258, 260, 262, 264, 266, 268, 270, 272, 274, 276, 278, 280, 282, 284, 286, 288, 290, 292, 294, 296, 298, 300, 302, 304, 306, 308, 310, 312, 314, 316, 318, 320, 322, 324, 326, 328, 330, 332, 334, 336, 338, 340, 342, 344, 346, 348, 350, 352, 354, 356, 358, 360, 362, 364, 366, 368, 370, 372, 374, 376, 378, 380, 382, 384, 386, 388, 390, 392, 394, 396, 398, 400, 402, 404, 406, 408, 410, 412, 414, 416, 418, 420, 422, 424, 426, 428, 430, 432, 434, 436, 438, 440, 442, 444, 446, 448, 450, 452, 454, 456, 458, 460, 462, 464, 466, 468, 470, 472, 474, 476, 478, 480, 482, 484, 486, 488, 490, 492, 494, 496, 498, 500, 502, 504, 506, 508, 510, 512, 514, 516, 518, 520, 522, 524, 526, 528, 530, 532, 534, 536, 538, 540, 542, 544, 546, 548, 550, 552, 554, 556, 558, 560, 562, 564, 566, 568, 570, 572, 574, 576, 578, 580, 582, 584, 586, 588, 590, 592, 594, 596, 598, 600, 602, 604, 606, 608, 610, 612, 614, 616, 618, 620, 622, 624, 626, 628, 630, 632, 634, 636, 638, 640, 642, 644, 646, 648, 650, 652, 654, 656, 658, 660, 662, 664, 666, 668, 670, 672, 674, 676, 678, 680, 682, 684, 686, 688, 690, 692, 694, 696, 698, 700, 702, 704, 706, 708, 710, 712, 714, 716, 718, 720, 722, 724, 726, 728, 730, 732, 734, 736, 738, 740, 742, 744, 746, 748, 750, 752, 754, 756, 758, 760, 762, 764, 766, 768, 770, 772, 774, 776, 778, 780, 782, 784, 786, 788, 790, 792, 794, 796, 798, 800, 802, 804, 806, 808, 810, 812, 814, 816, 818, 820, 822, 824, 826, 828, 830, 832, 834, 836, 838, 840, 842, 844, 846, 848, 850, 852, 854, 856, 858, 860, 862, 864, 866, 868, 870, 872, 874, 876, 878, 880, 882, 884, 886, 888, 890, 892, 894, 896, 898, 900, 902, 904, 906, 908, 910, 912, 914, 916, 918, 920, 922, 924, 926, 928, 930, 932, 934, 936, 938, 940, 942, 944, 946, 948, 950, 952, 954, 956, 958, 960, 962, 964, 966, 968, 970, 972, 974, 976, 978, 980, 982, 984, 986, 988, 990, 992, 994, 996, 998, 1000, 1002, 1004, 1006, 1008, 1010, 1012, 1014, 1016, 1018, 1020, 1022, 1024, 1026, 1028, 1030, 1032, 1034, 1036, 1038, 1040, 1042, 1044, 1046, 1048, 1050, 1052, 1054, 1056, 1058, 1060, 1062, 1064, 1066, 1068, 1070, 1072, 1074, 1076, 1078, 1080, 1082, 1084, 1086, 1088, 1090, 1092, 1094, 1096, 1098, 1100, 1102, 1104, 1106, 1108, 1110, 1112, 1114, 1116, 1118, 1120, 1122, 1124, 1126, 1128, 1130, 1132, 1134, 1136, 1138, 1140, 1142, 1144, 1146, 1148, 1150, 1152, 1154, 1156, 1158, 1160, 1162, 1164, 1166, 1168, 1170, 1172, 1174, 1176, 1178, 1180, 1182, 1184, 1186, 1188, 1190, 1192, 1194, 1196, 1198, 1200, 1202, 1204, 1206, 1208, 1210, 1212, 1214, 1216, 1218, 1220, 1222, 1224, 1226, 1228, 1230, 1232, 1234, 1236, 1238, 1240, 1242, 1244, 1246, 1248, 1250, 1252, 1254, 1256, 1258, 1260, 1262, 1264, 1266, 1268, 1270, 1272, 1274, 1276, 1278, 1280, 1282, 1284, 1286, 1288, 1290, 1292, 1294, 1296, 1298, 1300, 1302, 1304, 1306, 1308, 1310, 1312, 1314, 1316, 1318, 1320, 1322, 1324, 1326, 1328, 1330, 1332, 1334, 1336, 1338, 1340, 1342, 1344, 1346, 1348, 1350, 1352, 1354, 1356, 1358, 1360, 1362, 1364, 1366, 1368, 1370, 1372, 1374, 1376, 1378, 1380, 1382, 1384, 1386, 1388, 1390, 1392, 1394, 1396, 1398, 1400, 1402, 1404, 1406, 1408, 1410, 1412, 1414, 1416, 1418, 1420, 1422, 1424, 1426, 1428, 1430, 1432, 1434, 1436, 1438, 1440, 1442, 1444, 1446, 1448, 1450, 1452, 1454, 1456, 1458, 1460, 1462, 1464, 1466, 1468, 1470, 1472, 1474, 1476, 1478, 1480, 1482, 1484, 1486, 1488, 1490, 1492, 1494, 1496, 1498, 1500, 1502, 1504, 1506, 1508, 1510, 1512, 1514, 1516, 1518, 1520, 1522, 1524, 1526, 1528, 1530, 1532, 1534, 1536, 1538, 1540, 1542, 1544, 1546, 1548, 1550, 1552, 1554, 1556, 1558, 1560, 1562, 1564, 1566, 1568, 1570, 1572, 1574, 1576, 1578, 1580, 1582, 1584, 1586, 1588, 1590, 1592, 1594, 1596, 1598, 1600, 1602, 1604, 1606, 1608, 1610, 1612, 1614, 1616, 1618, 1620, 1622, 1624, 1626, 1628, 1630, 1632, 1634, 1636, 1638, 1640, 1642, 1644, 1646, 1648, 1650, 1652, 1654, 1656, 1658, 1660, 1662, 1664, 1666, 1668, 1670, 1672, 1674, 1676, 1678, 1680, 1682, 1684, 1686, 1688, 1690, 1692, 1694, 1696, 1698, 1700, 1702, 1704, 1706, 1708, 1710, 1712, 1714, 1716, 1718, 1720, 1722, 1724, 1726, 1728, 1730, 1732, 1734, 1736, 1738, 1740, 1742, 1744, 1746, 1748, 1750, 1752, 1754, 1756, 1758, 1760, 1762, 1764, 1766, 1768, 1770, 1772, 1774, 1776, 1778, 1780, 1782, 1784, 1786, 1788, 1790, 1792, 1794, 1796, 1798, 1800, 1802, 1804, 1806, 1808, 1810, 1812, 1814, 1816, 1818, 1820, 1822, 1824, 1826, 1828, 1830, 1832, 1834, 1836, 1838, 1840, 1842, 1844, 1846, 1848, 1850, 1852, 1854, 1856, 1858, 1860, 1862, 1864, 1866, 1868, 1870, 1872, 1874, 1876, 1878, 1880, 1882, 1884, 1886, 1888, 1890, 1892, 1894, 1896, 1898, 1900, 1902, 1904, 1906, 1908, 1910, 1912, 1914, 1916, 1918, 1920, 1922, 1924, 1926, 1928, 1930, 1932, 1934, 1936, 1938, 1940, 1942, 1944, 1946, 1948, 1950, 1952, 1954, 1956, 1958, 1960, 1962, 1964, 1966, 3420, 3422, 3424, 3426, 3428, 3430, 3432, 3434, 3436, 3438, 3440, 3442, 3444, 3446, 3448, 3450, 3452, 3454, 3456, 3458, 3460, 3462, 3464, 3466, 3468, 3470, 3472, 3474, 3476, 3478, 3480, 3482, 3484, 3486, 3488, 3490, 3492, 3494, 3496, 3498, 3500, 3502, 3504, 3506, 3508, 3510, 3512, 3514, 3516, 3518, 3520, 3522, 3524, 3526, 3528, 3530, 3532, 3534, 3536, 3538, 3540, 3542, 3544, 3546, 3548, 3550, 3552, 3554, 3556, 3558, 3560, 3562, 3564, 3566, 3568, 3570, 3572, 3574, 3576, 3578, 3580, 3582, 3584, 3586, 3588, 3590, 3592, 3594, 3596, 3598, 3600, 3602, 3604, 3606, 3608, 3610, 3612, 3614, 3616, 3618, 3620, 3622, 3624, 3626, 3628, 3630, 3632, 3634, 3636, 3638, 3640, 3642, 3644, 3646, 3648, 3650, 3652, 3654, 3656, 3658, 3660, 3662, 3664, 3666, 3668, 3670, 3672, 3674, 3676, 3678, 3680, 3682, 3684, 3686, 3688, 3690, 3692, 3694, 3696, 3698, 3700, 3702, 3704, 3706, 3708, 3710, 3712, 3714, 3716, 3718, 3720, 3722, 3724, 3726, 3728, 3730, 3732, 3734, 3736, 3738, 3740, 3742, 3744, 3746, 3748, 3750, 3752, 3754, 3756, 3758, 3760, 3762, 3764, 3766, 3768, 3770, 3772, 3774, 3776, 3778, 3780, 3782, 3784, 3786, 3788, 3790, 3792, 3794, 3796, 3798, 3800, 3802, 3804, 3806, 3808, 3810, 3812, 3814, 3816, 3818, 3820, 3822, 3824, 3826, 3828

located within the outturned marginal portion of
the upper and lower sole members, and an
opening in its forepart extending through both
layers, an outer sole member having a projec-
tion on its outermost corner, the opening being
in the inner sole member, and a line of stitching
securing together the outturned margin of the
upper, the marginal portion of the outer layer of

the upper and the inner sole member, the outer sole
member having a projection having a layer of cushioning material
thereon, and a line of stitching securing together 30
the outturned margin of the upper, the marginal
portion of the outer sole member, the inner sole member,
and the marginal portion of the outer sole
member.

HARRY C. KING. 35
